PROCESS OF EXTRACTING AROMATIC HYDROCARBONS

Arthur P. Lien, Hammond, Ind., and Bernard L. Evering, Chicago, Ill., assignors to Standard Oil Company, Chicago, Ill., a corporation of Indiana

Application December 27, 1946, Serial No. 718,854

11 Claims. (Cl. 196—14.25)

1
This invention relates to the treatment of organic materials, and more particularly to the refining of organic materials containing mixtures of hydrocarbons, such as aromatic, paraffinic, naphthenic and/or olefinic hydrocarbons to selectively extract therefrom the aromatic hydrocarbons. It relates still more particularly to the selective extraction of aromatic hydrocarbons from petroleum fractions containing the same.

The separation of aromatic hydrocarbons from paraffinic, naphthenic and/or olefinic hydrocarbons in materials containing the same find application in many fields. Among the many possible specific applications of the invention are the treatment of petroleum cycle stocks to provide less refractory stocks for subsequent thermal or catalytic cracking operations. Other specific applications will be readily apparent.

It is an object of the present invention to provide a method of selectively separating aromatic hydrocarbons from paraffinic, naphthenic and/or olefinic hydrocarbons in a mixture containing the same.

Still another object of the invention is to provide an improved method of refining petroleum fractions to separate therefrom undesirable aromatic hydrocarbons.

A still further object of the invention is to provide an effective method of refining hydrocarbons.

Other objects and advantages of the invention will become apparent from the following description thereof read in conjunction with the accompanying drawings which form a part of the specification and in which

Figure 1 is a flow-diagram of one method of carrying out the invention, and

Figure 2 is a flow-diagram of a modified method of carrying out the invention.

In accordance with the present invention aromatic hydrocarbons are selectively separated from a mixture containing non-aromatic hydrocarbons, such as paraffinic, naphthenic and/or olefinic hydrocarbons by extracting such materials with a complex of boron fluoride (BF_3) with an oxygenated organic compound, and the halogen, preferably chlorine, derivatives of such oxygenated organic compounds. The aromatic hydrocarbons and the non-aromatic hydrocarbons subject to separation by the present invention may be normally liquid or liquid under existing operating pressures. While complexes of BF_3 with aliphatic or aromatic or oxygenated compounds can be used, we prefer to employ complexes of BF_3 with an oxygenated alkane compound selected from the class consisting of ethers, esters and acids having not more than about 5,

and preferably 3, carbon atoms in the alkyl group, and the halogen, preferably chlorine, derivatives thereof.

Specific examples of organic oxygenated compounds which can be employed when forming the boron fluoride complexes are the following:

Methyl ether	Butyl formate
Ethyl ether	Ethyl propionate
Propyl ether	Formic acid
Butyl ether	Acetic acid
Amyl ether	Propionic acid
Phenol	Anisol
Methylethyl ether	Pyran
Methyl acetate	Tri-
Ethyl acetate	Tetra-
Propyl acetate	Penta-
Amyl acetate	methylene
Methyl formate	oxides
Ethyl formate	

and the halogenated, preferably chlorinated, derivatives of the above as for example, B,B' dichloroethyl ether (Chlorex), chloroacetic acid, etc.

While complexes of boron fluoride with oxygenated organic compounds as a class are effective solvents for effecting a separation between aromatic hydrocarbons and paraffinic, olefinic and/or naphthenic hydrocarbons, they are all not equal in their effectiveness and selectivity since the degree of selectivity and effectiveness may vary with different complexes with the composition of the mixture being extracted and with the conditions of extraction, as will be hereinafter described.

The boron fluoride complexes are readily prepared by bubbling a slight molar excess of boron fluoride through the oxygenated compound, e. g. ether, ester, acid, etc., and then subjecting the mixture to reduced pressure to remove the excess boron fluoride. In some cases, it is desirable to carry out the BF_3 stripping step at lower than room temperature in order to avoid decomposition of the complex. The residual product is a complex of a mol to mol ratio of boron fluoride to the oxygenated organic compound. The complexes suitable for the herein described invention are liquid or solids which melt slightly above room temperature, e. g. about 100° F. to about 150° F. A small amount, sufficient to give a partial pressure of at least 15 pounds, and preferably from about 15 to 500 pounds, per square inch, of boron fluoride may be used in conjunction with the herein described complexes, in order to effect increased extraction, e. g. of higher molecular weight aromatics.

The choice of any particular organic oxygen-

ated compounds used in forming the boron fluoride complex will depend upon the feed to be treated, with due consideration being given to the boiling point of the complex in relation to the boiling range of the feed material and the extract to be obtained therefrom. For example, the boron fluoride-methyl ether or boron fluoride-ethyl ether complexes boil at relatively low temperatures, namely 258° to 262° F. Therefore, if the extracted material boils in this temperature range, it is preferable to use a higher boiling complex, for example the adduct of boron fluoride with a halogenated methyl ethyl ether. Of course, under some conditions complexes having a boiling point lower than that of the extracted material may be used, in which case the complex can be recovered by distilling or flashing off the same from the extract.

The extraction can be carried out over a wide temperature range, of about 50° F. to about 150° F. or higher, and preferably from about 70° F. to about 100° F. The quantity of complex used should be sufficient to give a diphasic separation and depending upon the material being extracted can vary from 10 volume percent to about 200 volume percent or more, based on hydrocarbon feed, and preferably from about 50 volume percent to about 100 volume percent, although in some cases as little as 5 volume percent or less will give a satisfactory diphasic separation. A pressure sufficient to keep the materials in a liquid phase should be maintained in the extractor. In the extraction of heavier stocks, such as for example lubricating stocks or in separation of aromatics and olefins, improved selectivity can be attained under certain conditions by the addition to the extraction mixture of an inert paraffin hydrocarbon diluent, such as for example pentane, hexane or heptane.

The following procedure of extracting a highly aromatic, relatively low-boiling hydrocarbon feed stock with a boron fluoride-ethyl acetate complex is given by way of illustration only and is not intended to be a limitation of our invention. Referring to Figure 1, a highly aromatic, low-boiling hydrocarbon feed stock is introduced through a line 10 into the bottom portion of an extractor 11 and countercurrently contacted with a boron fluoride-ethyl acetate complex introduced into the upper portion of the extractor 11 through a line 12. The extractor 11 is suitably a packed column, although other known suitable means of obtaining intimate contact can be employed. A raffinate is removed overhead from the extractor 11 through a line 13 and introduced into a settler 14 wherein any carryover complex is settled out and returned to the extractor 11 through line 15. The raffinate, free of carryover complex, is withdrawn from the separator 14 through line 16 and introduced into the bottom portion of a still 17 provided with suitable heating means such as heating coil 18. The raffinate substantially freed of aromatics is taken off overhead through a line 19. The bottoms from the still 17 comprising a boron fluoride-ethyl acetate complex is withdrawn from still 17 through a line 20 and introduced into the complex storage tank 21. If the hydrocarbon feed stock distills above the boiling point of the complex, the aromatic-free raffinate is withdrawn as bottoms and the complex is taken overhead. Still 17 may be operated under reduced pressure.

The extract from the extractor 11 is withdrawn therefrom through line 22 and introduced into still 23 equipped with suitable heating means,

such as heating coil 24. Still 23 may be operated at sub-atmospheric pressure. A fraction comprising substantially aromatic hydrocarbons is removed overhead from still 23 through line 25, while the complex, substantially free of aromatics, is withdrawn through line 26 and either introduced into the complex storage tank 21 through line 27, or recycled to the extractor 11 through line 28. Complex from storage tank 21 is introduced into the extractor 11 through lines 28, 29 and 12. In order to supply make-up boron fluoride complex, boron fluoride is introduced into the storage tank 21 through line 30 and ethyl acetate is added through line 31.

The foregoing example illustrates a method of carrying out the herein described invention in which the boron fluoride complex is not decomposed by distillation. However, certain boron fluoride complexes are decomposed into boron fluoride and the oxygenated organic compound when subjected to distillation, even vacuum distillation. When employing such complexes they cannot be recovered as in the hereinbefore described method. The following example illustrates one method of carrying out the invention employing a boron fluoride complex which is decomposable under distillation conditions. For the purpose of illustration, the following procedure provides a method of carrying out the invention employing as the solvent a boron fluoride-beta beta dichloroethyl ether complex hereinafter referred to as the boron fluoride-Chlorex complex.

Referring to Figure 2, the feed to be extracted, for example highly refractory aromatic cycle stock, is introduced through line 110 into the bottom portion of extraction tower 111 and countercurrently contacted with a boron fluoride-Chlorex complex introduced into the upper portion of the tower 111 through line 112. A temperature of about 40 to 90° F. is maintained in the extraction tower 111. The raffinate from the extraction tower 111 is removed overhead through line 113 to a settler 114, wherein any entrained boron fluoride-Chlorex complex is settled out and recycled to tower 111 through lines 115 and 116, or may be passed through lines 115 and 117 to a complex recovery unit hereinafter described. The raffinate from the settler 114 is passed through line 118 to a boron fluoride stripper 119 provided with suitable heating means such as a heating coil 120, wherein any small amount of dissolved boron fluoride complex is decomposed by heating and the boron fluoride is removed overhead through lines 121 and 122 to a boron fluoride-Chlorex mixer 123. The bottoms from the stripper 119 are withdrawn through line 124 to a fractionator 125, provided with suitable heating means such as a heating coil 126, wherein the Chlorex is taken overhead through lines 127 and 128 to the boron fluoride-Chlorex mixer 123. The raffinate, freed of boron fluoride and Chlorex, is removed from the tower 125 through line 129. If a light hydrocarbon diluent has been used it may be removed as an overhead stream from the top of the fractionator 125 and the Chlorex taken off as a higher boiling side stream. Obviously, in the event the hydrocarbon product has a lower boiling point than the Chlorex, the hydrocarbon will be taken overhead from the fractionator 125 and the Chlorex will be withdrawn from the fractionator 125 as a bottom and passed to the boron fluoride-Chlorex mixer.

The extract from the extractor tower 111 com-

prising boron fluoride-Chlorex complex and the extracted material from the feed is removed from tower 111 through line 130, and introduced into a stripper 131 provided with suitable heating means such as heating coil 132 for maintaining a bottom temperature of 180° F. to 400° F. in the stripper. Boron fluoride-Chlorex complex from the settler 114 may be introduced into the stripper 131 through lines 117 and 130. Boron fluoride is taken overhead through line 133 and passed via line 122 to the boron fluoride-Chlorex mixer 123. Bottoms from the stripper 131 are withdrawn through line 134 to fractionating tower 135, provided with suitable heating means such as heating coil 136, wherein the separation is made between the organic extracted material and the Chlorex. Chlorex from the fractionator 135 is taken overhead through line 137 and introduced via line 128 to the boron fluoride-Chlorex mixer 123. The extracted organic material is withdrawn from the fractionating tower 135 through line 138. Alternately, the Chlorex may be withdrawn as bottom product if the boiling range of the extract is below the boiling point of Chlorex.

The boron fluoride-Chlorex mixer is operated under cooling conditions to prevent excessive temperature due to the heat of reaction between the boron fluoride and Chlorex. Make-up boron fluoride is introduced to the mixer through line 139 and the make-up Chlorex through line 140 in sufficient quantity to maintain a stoichiometric ratio of the components of the complex. The boron fluoride-Chlorex complex from mixer 123 is recycled to the extraction tower 111 through lines 141 and 142. Although the boron fluoride stripper and the Chlorex fractionator have been shown as separate towers, a single tower may be used.

The applicability of boron fluoride-complexes to the separation of aromatics from paraffin hydrocarbons is demonstrated by the data in Table I below. The data presented therein were obtained in a one step extraction of blends of 50% heptane and 50% benzene, ortho xylene, and meta xylene with complexes of boron fluoride and various oxygenated organic compounds.

While the data in Table I are based on a single step extraction, an improvement can be obtained by carrying out the extraction in a number of stages. This improvement is illustrated by the data in Table II, in which a blend of 50% benzene and 50% heptane was extracted with boron fluoride-ethyl ether and boron fluoride-propyl acetate complexes in one and four stages, using a total of one volume of complex to one volume of the hydrocarbon mixture in each case.

TABLE II

One stage vs. four stage extraction of 50% n-C₇-50% C₆H₆ mixture

	Complex	Total Extraction, Per Cent	
		1 Stage	4 Stage
20	BF ₃ -Ethyl Ether	54.2	79.1
	BF ₃ -Propyl Acetate	55.6	77.1

The above data demonstrate that with a given total quantity of complex, multiple stage extraction results in an increase in the quantity of aromatics extracted from a hydrocarbon mixture containing the same.

The application of the present invention to the extraction of aromatics from a mixture of aromatics and long chain paraffins is demonstrated by the data in Table III, in which a mixture of 50% benzene and 50% cetane was extracted with an equal volume of boron fluoride-ethyl ether complex in one and four stages.

The foregoing data demonstrate the effectiveness of complexes of boron fluoride and an oxygenated organic compound in extracting polynuclear aromatic hydrocarbons from a mixture containing paraffinic, naphthenic and/or olefinic hydrocarbons.

The degree of extraction to be obtained with a complex mixture of higher molecular weight aromatics, paraffins, naphthenes and olefins is demonstrated in Table V by a number of experiments carried out on a sample of highly refractory gas oil cycle stock, obtained by multiple recycling of East Texas naphthenic gas oil in a catalytic cracking process.

TABLE V

¹ Original East Texas gas oil from which cycle stock was obtained.

² Selectivity = ratio n_D^{20} divided by treating loss $\times 10^4$.

The measure of selectivity in the above experiments is shown as the ratio of index change to treating loss. It is seen that most of the complexes show about the same degree of selectivity, in direct contrast to the results on the lower molecular weight aromatics as shown in Table I. Thus, anisole which is entirely unsatisfactory for extraction of benzene or xylene because of extremely poor selectivity (Table I), effects a high degree of extraction of aromatics from cycle stock with a good selectivity.

In the case of aromatics in the gas oil range, the degree of extraction increases markedly with increase in molecular weight of the organic portion of the BF_3 complex. Thus with the ethers (ROR), there is a definite progression as R is changed from methyl- to ethyl- to propyl-. The same effect is noted in comparing the esters.

These effects, holding only for the higher molecular weight aromatics and in contrast to the data shown in Table I for benzene and xylene appear to be tied in with the relative degrees of dissociation of a given complex and therefore should be a function of the degree of availability of free BF_3 . This effect is demonstrated in run 7 where BF_3 gas was bubbled through a mixture

of cycle stock and BF_3 ethyl ether complex. Comparison of this run with run 6 shows that aromatic extraction is markedly increased over that obtained with BF_3 ethyl ether complex in the absence of excess BF_3 and this without attendant loss in selectivity. The results in run 7 indeed approach closely those obtained with the relatively highly dissociated BF_3 . Chlorex complex (run 8). Although the presence of free BF_3 increases the degree of extraction when used in conjunction with a BF_3 oxygen complex, it is seen from run 1 that BF_3 alone has little effect in aromatic removal.

The effect of multiple stage contacting is shown by run 11. In this case a given sample of the cycle stock was contacted with equal volumes of fresh BF_3 ethyl ether complex in 4 successive treats. Examination of the physical properties of the final raffinate shows it to be less aromatic (lower index and density) than the original gas oil from which the cycle stock was obtained. Our treating process, therefore, lends itself readily to extraction of a refractory cycle stock to produce a charging stock more amenable to cracking than the present gas oil feed.

While our invention is particularly adapted to the selective separation of aromatic hydrocarbons from mixtures containing the same, it is not limited thereto, since we have discovered that

complexes of boron fluoride and oxygenated compounds of the type herein described are effective in removing organic sulfur compounds, and color-forming bodies from organic materials, particularly hydrocarbons.

While we have described our invention with reference to certain specific embodiments thereof, the invention is not to be considered limited thereto, but includes within its scope such modifications as come within the appended claims.

We claim:

1. The method of extracting aromatic hydrocarbons from a mixture comprising normally liquid aromatic hydrocarbons and normally liquid non-aromatic hydrocarbons, comprising extracting said mixture at a temperature within the range of from about 50° F. to about 150° F. with a complex of boron fluoride with an oxygenated organic compound in sufficient quantity to form a diphasic separation, separating a fraction comprising essentially said non-aromatic hydrocarbons and a minor amount of said complex, and a fraction comprising essentially aromatic hydrocarbons dissolved in said complex, and separating said complex from said fractions.

2. The method of extracting aromatic hydro-

carbons from a mixture comprising normally liquid aromatic hydrocarbons and normally liquid non-aromatic hydrocarbons, comprising extracting said mixture at a temperature within the range of from about 50° F. to about 150° F. with a complex of boron fluoride with an oxygenated alkane compound having not more than about 5 carbon atoms in the alkyl group, in sufficient quantity to form a diphasic separation, separating a fraction comprising essentially said non-aromatic hydrocarbons and a minor amount of said complex, and a fraction comprising essentially aromatic hydrocarbons dissolved in said complex.

3. The method described in claim 2 in which the oxygenated alkane compound is an alkane ester.

4. The method described in claim 3 in which the alkane ester is ethyl acetate.

5. The method described in claim 2 in which the oxygenated alkane compound is an alkane ether.

6. The method described in claim 5 in which the alkane ether is an ethyl ether.

7. The method described in claim 6 in which the alkane ether is beta, beta dichloroethyl ether.

8. The method described in claim 2 in which the oxygenated alkane is an alkane acid.

9. The method of extracting aromatic hydrocarbons from a mixture comprising aromatic hydrocarbons and paraffinic hydrocarbons comprising extracting said mixture at a temperature within the range of from about 50° F. to about 150° F. with a complex of boron fluoride with an oxygenated alkane compound having not more than about 5 carbon atoms in the alkyl group in sufficient quantity to form a diphasic separation, separating a raffinate comprising essentially paraffinic hydrocarbons and said complex and an extract comprising essentially aromatic hydrocarbons, and said complex, and separating said complex from the raffinate and extract fractions.

10. The method of extracting aromatic hydrocarbons from a mixture comprising normally liq-

5

10

uid aromatic hydrocarbons and normally liquid non-aromatic hydrocarbons, comprising contacting said mixture at a temperature within the range of from about 50° F. to about 150° F. with a complex of boron fluoride and an oxygenated organic compound in sufficient quantity to form a diphasic separation, separating a raffinate fraction comprising essentially non-aromatic hydrocarbons and a minor amount of said complex and an extract fraction comprising essentially aromatic hydrocarbons dissolved in said complex and separating said complex from the raffinate and extract fraction.

11. The method of extracting high molecular weight polycyclic aromatic hydrocarbons from a mixture comprising normally liquid high molecular weight polycyclic aromatic hydrocarbons and normally liquid non-aromatic hydrocarbons, comprising contacting said mixture at a temperature within the range of from about 50° F. to about 150° F. with a solvent comprising essentially a complex of boron fluoride with an oxygenated organic compound, and an excess of boron fluoride sufficient to give a partial pressure of at least 15 pounds per square inch, separating a raffinate comprising essentially non-aromatic hydrocarbons and a small amount of said solvent and an extract comprising essentially aromatic hydrocarbons and said solvent, and separating said solvent from said raffinate and extract.
